UNITED STATES PATENT OFFICE.

ANDREW H. RYAN, OF MEDINA, OHIO.

DISTRIBUTING-NOZZLE.

1,152,225.

Specification of Letters Patent. Patented Aug. 31, 1915.

Application filed August 26, 1913. Serial No. 786,685.

To all whom it may concern:

Be it known that I, ANDREW H. RYAN, a citizen of the United States, residing at Medina, in the county of Medina and State 5 of Ohio, have invented certain new and useful Improvements in Distributing-Nozzles, of which the following is a specification.

My invention relates to improvements in distributing nozzles, the present embodiment being particularly designed and adapted for use in connection with sewage disposal plants in which the nozzles are arranged at intervals over the filtration bed the sewage being dispersed upwardly and 10 outwardly or radially, by the nozzle as it passes through the same from the riser pipe. These nozzles are liable to become clogged up by the solid matter of the sewage and it is necessary from time to time to remove the 15 obstructions in order to have the sewage plant operate to its full capacity.

The primary object of the invention is to provide a generally improved nozzle or distributing device of exceedingly simple, 20 cheap, and efficient construction, having its parts so arranged and disposed relative to each other as to permit the parts to be readily adjusted to meet the varying demands of actual service.

30 A further object of the invention is the provision of a filtration nozzle of this class having an improved removably mounted nozzle head bearing a spring resisted adjustably mounted spreader member, the latter with its connection being removably 35 mounted within the main body portion of the distributing nozzle, or at the upper end of the riser pipe.

A still further object is the provision of 40 an improved sewage distributing nozzle which, through its various adjustments, may be conformed to the demands of actual service in the various sewage disposal plants and more particularly one having a spreader 45 head which, through its adjustably mounted tension spring will automatically adjust itself to varying liquid pressures, within certain predetermined limits, as in day and night service and the like.

50 With the above mentioned and other ends in view, the invention consists in the novel

construction, arrangement, and combination of parts, hereinafter described, illustrated in one of its embodiments in the accompanying drawings, and particularly pointed out in 55 the appended claims.

Referring to the drawings, forming a part of this specification, Figure 1, is a vertical sectional view of the improved distributing nozzle, in its operative position, applied to 60 a riser pipe, the spreader member being shown in its closed position. Fig. 2, a similar view, partly in side elevation showing the manner in which the nozzle head and the improved adjustably mounted spreader 65 member and its connections may be removed for cleaning out, or for adjustment or repair. Fig. 3, a side elevation of the improved nozzle head. Fig. 4, a cross sectional view taken through line 4—4 of Fig. 1. Fig. 70 5, a top plan view of the improved nozzle head, the improved spreader member being removed.

Similar numerals of reference designate like parts throughout all the figures of the 75 drawings.

The improved nozzle comprises a main body portion of the tubular section 1, adapted to be disposed in a vertical position in and to project slightly above the filtration 80 bed 2, and to be removably mounted and connected to the riser pipe 3, said tubular section, in the present instance, being threaded at its lower end to thread into the upper end of the riser pipe 3. The tubular member or section 1, is threaded at its upper end and is provided with a threaded cap or nozzle head 4, the latter being provided with a centrally located outwardly flaring or beveled nozzle opening 4^a, adapted to be controlled or regulated by means of a conical 85 shaped spreader member 5. The spreader member 5, projects upwardly above the nozzle head 4, and is adapted to be seated in and to control the liquid issuing from the nozzle 90 opening.

The spreader member 5, is connected to a guide rod or stem 6, slidably mounted and vertically movable in a tubular guide sleeve 7, which guide sleeve is adjustably mounted 100 and secured, in the present instance, by means of a set of four adjusting screws 8,

the heads 8^a, of the latter being disposed in counter sunk screw openings of an auxiliary or inner tubular section 9, slidably and removably mounted in the main or outer tubular section 1.

When the improved nozzle is in operation, the upward movement of the conical shaped spreader member 5, is cushioned and adjusted through the medium of a spring 10, at 10 the lower end of the stem 6, said spring 10, being interposed between the lower end of the tubular guide member 7, and adjusting and lock nuts 11, adjustably threaded upon the lower end of the guide stem 6. Should 15 any foreign matter or substances get into the nozzle opening 4^a, or should it be desired to clean the nozzle or to remove the parts for inspection or repair, the head cap or nozzle head 4, may be readily unscrewed 20 and as the nozzle head is lifted it will carry with it the stem 6, and tubular guide sleeves 7, together with the supplemental or inner tubular section 9, as shown in Fig. 2, so that all these various inner parts may be cleaned 25 or adjusted or repaired, as desired. The two sets of adjusting screws 8, at the top and bottom, respectively, of the inner tubular section 9, enable the guide sleeve 7, and guide stem 6, to be readily adjusted and thus 30 to perfectly centralize or adjust the spreader member 5, in accordance with requirements, thus insuring an even and uniform distribution of the liquid material from the nozzle opening 4^a, this adjustment being a particular 35 advantage in the event of the main tubular section 1, not being disposed in or getting out of an exact or true vertical position, or in the event of the liquid pressure being somewhat unequal at the nozzle opening 4^a. The lower end of the inner tubular section 9, in the present instance, is rested on stop or supporting screws 12, extending through the lower end of the tubular section 1. 40

45 By reason of the above described construction and the various adjustable features thereof, it will be apparent that the parts may be readily adjusted to conform to the varying demands of actual service, and that 50 the spreader member 5, may be readily adjusted and its sensitiveness regulated through the medium of the adjusting nuts 11, which latter also act to adjust the tension upon the spring 10, so that the spreader member 5, head through its adjustably mounted tension spring will automatically adjust itself to varying liquid pressures within certain predetermined limits, as for example,—as in day and night service, the liquid pressure 55 being greater during the day than during the night.

From the foregoing description, taken in connection with the accompanying drawings, the operation and advantages of my invention will be readily understood.

Having thus described one of the embodiments of my invention, what I claim and desire to secure by Letters Patent is,—

1. In a distributing nozzle, a tubular section, a nozzle head provided with an outwardly flaring nozzle opening, a conical shaped spreader member projecting above and adapted to control said opening, a guide stem connected to said spreader member, a removable inner tubular section carrying an 70 adjustably mounted guide sleeve surrounding said guide stem, a spring surrounding said guide stem and abutting against said guide sleeve, and means for adjusting the tension of said spring.

2. A distributing nozzle, comprising a pipe section, an internally threaded removable nozzle head mounted on the pipe section and provided with an outwardly flaring nozzle opening, a vertical movable spreader member seated in and projecting above said nozzle opening and provided with a guide stem extending into said pipe section, an independent supporting section separate from said nozzle head and provided with a 80 guide sleeve surrounding said guide stem and removable with the latter when said nozzle head and spreader member are removed, adjusting means at the lower end of said guide stem, and a spring interposed between said adjusting means and the lower end of said guide sleeve.

3. In a distributing nozzle, a pipe section, a removable nozzle provided with an outwardly flaring nozzle opening, an upwardly 100 projecting conical spreader seated in and over hanging said nozzle opening, a supporting section removably mounted in said pipe section, a guide stem vertically movable in said supporting section and connected to said spreader member, means carried by said supporting section for adjusting and centralizing said spreader member relative to said nozzle opening, and means for removably securing and cushioning said guide stem 105 in said supporting section.

4. In a distributing nozzle, a pipe section, an internally threaded removable nozzle head detachably connected therewith and provided with an outwardly flaring nozzle opening, a conical shaped spreader member mounted in said opening, a guide stem carried by said spreader member, a separate supporting section within said pipe section and surrounding and guiding said guide stem and being removable with the latter when said nozzle head and spreader member are removed, and means for removably securing and cushioning said guide stem in 115 said supporting section.

5. In a distributing nozzle, a tubular section, a nozzle head detachably and removably mounted on the outside of said tubular section and provided with an outwardly flaring nozzle opening, a conical shaped 120

spreader member projecting above and adapted to control said nozzle opening, a guide stem connected to and carried by said spreader member, a separate independent inner section surrounding said guide stem and removable with and carried by the latter when said nozzle head and spreader member are removed from said tubular section, a spring surrounding said guide stem and abutting against said removable inner section, and means on said guide stem below

said spring for adjusting the tension of the latter and for removably securing said guide stem and spreader member independently of said nozzle head.

15

In testimony whereof I have affixed my signature in presence of two witnesses.

ANDREW H. RYAN.
